CLAIM

The ornamental design for a car door side storage box, substantially as shown and described.

DESCRIPTION

FIG. 1 is a front perspective view of car door side storage box, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate portions of the car door side storage box which form no part of the claimed design.
